UNITED STATES PATENT OFFICE.

ANDREW JACKSON STONE, OF NEW YORK, N. Y., ASSIGNOR, BY MESNE ASSIGNMENTS, TO AMERICAN ORDNANCE CORPORATION, OF NEW YORK, N. Y., A CORPORATION OF DELAWARE.

PROJECTILE FOR USE WITH DEPTH-CHARGE PROJECTORS.

Application filed April 3, 1919. Serial No. 287,103.

To all whom it may concern:

Be it known that I, ANDREW JACKSON STONE, a citizen of the United States, residing at New York city, in the State of New York, have invented certain new and useful Improvements in Projectiles for Use with Depth-Charge Projectors; and I do hereby declare the following to be a full, clear, and exact description of the invention, such as will enable others skilled in the art to which it appertains to make and use the same.

My present invention relates to improvements in projectiles for use with depth charge projectors, and it is intended to provide an arrangement comprising a can containing a depth charge and a holder therefor, which together are launched from any of the various types of depth charge guns or projectors which are used or have been used in throwing large charges of high explosive through short distances from a gun platform.

My present invention is especially adapted for use with the well-known Y-gun of my United States Letters Patent No. 1,311,780, issued July 29, 1919, the application for which (Serial No. 192,130, filed September 19, 1917) was copending herewith. My present invention is in part illustrated and described in said letters patent and the present application is correspondingly in part divisional from the said copending application.

While the invention is especially adapted for use in connection with the type of Y-guns hereinbefore referred to, from which two depth charges are simultaneously expelled in opposite directions, the invention is also applicable for use with a single barrel depth charge projector, such as has been largely used in the various naval services during the great war recently closed.

My invention will be more fully understood after reference to the accompanying drawings, in which like parts are indicated by similar reference symbols throughout the several views.

Figure 1 shows an end view of one of the well known Y-guns described in my application aforesaid, both barrels being provided with the projectiles, and one of the bar-

rels and the arbor or piston of the projectile being shown in section.

Figure 2 is a perspective view of the projectile shown in Figure 1, part of the stem or arbor being cut away.

Figure 3 shows a section along the line 3-3 of Figure 2, and looking in the direction of the arrows; and

Figure 4 shows a section along the line 4-4 of Figure 3, and looking in the direction of the arrows, the can containing the high explosive being indicated in dotted lines.

A represents the Y-gun carried by any suitable pedestal A' mounted on the gun platform or support B. The gun is provided with two smooth bore barrels A², set at any suitable angle, preferably 45° from the horizontal. C represents the breech mechanism of the piece, but the details and construction of the gun and breech mechanism are fully described in my application aforesaid, and my present invention relates entirely to the projectile launched from that gun or any other suitable gun, for hurling high explosive charges a short distance.

The projectile consists of a hollow stem or arbor D, which is in the form of a hollow cylinder closed at its lower end as at d, and having secured to its upper end the curved plate D' into which the cylindrical can E containing the high explosive charge fits snugly; this arbor and plate thus resemble a hod for carrying bricks.

The can or container and its contents comprise the ordinary well known depth bomb, as largely used in the late war with Germany, the can being filled with a main charge of high explosive, and a detonator adapted to explode the main charge when the bomb reaches a predetermined depth.

These details are well known in naval science, and need not be further described herein.

The can or container containing the high explosive is secured to this support in any convenient way, as by the fixed hook F engaging in the chine of the can, and the adjustable hook F'. This latter hook is of generally similar construction to the hook F, but is slotted as at f°, and clamped in place by bolts G and lock nuts g.

In order to assemble the parts of the projectile, the nuts *g* are eased up, permitting the hook *F*' to be moved outward to the desired distance, then the chine at one end of the can is caused to engage the hook *F*, and the hook *F*' is then moved to a position to engage the chine at the other end of the can, then the lock nuts are set up and the projectile is ready for being hurled as a complete unit.

Attached to the can *E*, I provide a suitable arrangement for exploding the charge in said can when it reaches a predetermined depth, but such mechanism is well known in the art and is not a part of my present invention, this invention relating merely to the improvements for hurling the can to the desired distance from the gun platform, which would ordinarily be the deck of a torpedo boat destroyer or submarine chaser, or other vessel.

The operation of the apparatus is as follows:

The gun being loaded, the arbor *G* of the projectile being inserted in the gun barrels, after the manner of pistons as shown in Figure 1, and the propelling charge being inserted in the powder chamber of the gun at the lower end of each of the barrels, as described in my application aforesaid, the piece is fired. The powder gases generated in the powder chamber will cause the arbors *D* to move like pistons outwards, imparting an accelerating speed to each complete projectile carrying its heavy charge of high explosive, and the two projectiles will be hurled through a suitable distance to either side of the gun platform. This distance will depend upon the amount and quality of the powder used, the size of the powder chamber, and other factors, described in my application aforesaid, but these are not a part of the invention claimed herein.

After leaving the gun, the heavy cans containing the high explosive will continue to move sideways through the air, like arrow heads, following, of course, a curved trajectory, while the hollow arbors *D* will serve, like the stems of arrows, to prevent the projectiles from tumbling in flight.

By having the cylindrical surface of the container *E* exposed to the maximum pressure of the air, when the projectile is first launched, the advantage of the well known strength of the cylinder to compression is secured, so that a light container may be used.

The arbor *D*, acting as a piston, will serve to guide the projectile in the proper direc-

tion until it leaves the gun, when the projectile will follow its trajectory through the air, as hereinbefore described.

By having these hollow arbors of cylindrical form as shown, after the gun is fired, pressure will be continuously applied to the base of the projectile until the arbor leaves the gun, and sufficient velocity may be imparted to the projectile without subjecting the same to any sudden or severe shock, and also without subjecting the gun platform to any excessive downward thrust.

Owing to the low pressures used, the metal parts of the projectile may be made comparatively thin and light, so that a correspondingly large bursting charge for a given weight of projectile may be employed.

While I prefer to have the high explosive contained in cylindrical cans, known in naval phraseology as "ash cans", the high explosive charge may be enclosed in any suitable shaped conveyers, and the supporting head to the arbor may be shaped to fit the container.

I have shown a simple form of attaching the can to the arbor head, but any suitable means for attaching the cans to said head might be adopted if desired.

It will be obvious that various modifications might be made in the herein described construction, combination and arrangement of parts which could be used without departing from the spirit of my invention, and I do not mean to limit the invention to such details of construction except as particularly pointed out in the claims.

Having thus described my invention what I claim and desire to secure by Letters Patent of the United States is:

1. A projectile for depth charge projectors comprising an arbor adapted to project into the barrel of the piece and to form a piston in said barrel, a saddle carried by said arbor, a container containing a main charge of high explosive and a detonator, and a pair of hooks secured to said saddle adjustable relative to each other for attaching said container to said saddle.

2. A projectile for depth charge projectors comprising an arbor adapted to project into the barrel of the piece and to form a piston in said barrel, a saddle carried by said arbor, a container containing a main charge of high explosive and a detonator, and having a rim at each end thereof, and a pair of hooks on said saddle and taking over said rim.

ANDREW JACKSON STONE.
